HOT JOURNAL DETECTING APPARATUS

Joseph C. McCune, Edgewood, Pa., assignor to
The Westinghouse Air Brake Company, Wil-
merding, Pa., a corporation of Pennsylvania

Application November 22, 1944, Serial No. 564,673

4 Claims. (Cl. 246—169)

1

This invention relates to hot journal detecting apparatus and has particular relation to apparatus for automatically signaling the engineer on the locomotive of a train of railroad cars whenever an abnormal heat condition occurs in an axle journal on any of the cars of the train.

Railroads have long sought a simple and inexpensive apparatus for apprising the engineer or other member of a train crew of the occurrence of a "hot box" or abnormally high heat condition in the axle journal on any of the cars of the train because hot boxes not only damage the parts of the journal but may even result in breakage of an axle and possible wreckage of a train due to derailment of a car following breakage of the axle. Various devices and systems have been proposed for this purpose. So far as is known, the systems proposed for apprising the engineer of the occurrence of a hot box on any car of a train have necessitated the employment of train wires extending from car to car throughout the train to the locomotive for the purpose of electrically controlling an electrically actuated signal device on the locomotive.

It is an object of my present invention to provide a system for apprising the engineer on the locomotive of a train of cars of the occurrence of an abnormal heat condition in the axle journals on any car without the necessity of employing train wires, thereby eliminating the expense as well as the practical difficulties incidental to the use of train wires.

In carrying out this object of my invention I employ means responsive to the occurrence of an abnormal heat condition in the axle journal on any of the cars for effecting a variation of the pressure of fluid in the usual signal pipe carried on most railroad passenger trains in a manner to cause a characteristic operation of the audible signal device or whistle on the locomotive distinct from the type of audible signal produced by the whistle on the locomotive in response to the manual operation of the usual discharge valve on the cars by a member of the train crew. It is thus possible for the engineer to be immediately apprised by a characteristic audible signal of the occurrence of the abnormal heat condition in any axle journal on any car of the train, so that he may immediately stop the train and take the necessary steps to correct this condition before proceeding further.

It is a further object of my invention to provide apparatus of the character indicated in the foregoing object and additionally characterized by

2

audible and visible signaling apparatus on the individual cars of a train.

It is another object of my invention to provide a novel apparatus for detecting an abnormal heat condition in a bearing or journal characterized in that it is operative in response to a predetermined and substantially uniform rise of temperature in a journal above the ambient or atmospheric temperature outside the journal.

10 In heretofore known hot box detecting apparatus, such as those of the fusible element type, the abnormal heat condition in the journal is indicated only when a predetermined abnormally high temperature is exceeded. In the case of railroad trains operating in climates having a wide range of climatic temperatures, such apparatus inherently delays the indication of the abnormal heat condition in the journal when climatic or atmospheric temperatures are very low due to the greater rise from the normal operating temperature of the journal to the abnormally high temperature.

With such heretofore known types of hot box detecting apparatus it is therefore possible that 25 it may be too late to take the necessary steps to correct the condition after such condition is indicated because of the fact that damage to the journal may already have occurred. My present invention therefore obviates this difficulty and insures adequate notice to the engineer at all times 30 of an abnormal heat condition in the axle journals on any of the cars by recognizing the abnormal heat condition on the basis of a certain substantially uniform rise in temperature in the journal 35 above the atmospheric temperature outside the journal, which rise is somewhat above the usual normal operating temperature of the journal for a given atmospheric temperature.

In those cases where a signal pipe is not available on a train, such as freight trains, my present invention employs the usual brake pipe on the train for signaling the engineer by means of an automatically produced brake application effected by reduction of the pressure in the brake pipe 45 in response to the occurrence of a hot box condition.

The above objects and other objects of my invention which will be made apparent hereinafter, are attained by means of apparatus subsequently 50 to be described and shown in the accompanying drawings wherein

Figure 1 is a diagrammatic view, with parts in section, showing a hot box signaling apparatus that employs the signal pipe on a train of cars 55 and that also shows the details of my novel ab-

normal heat condition detecting apparatus in association with an axle journal.

Figure 2 is an enlarged sectional view, taken on the line 2-2 of Figure 1, showing further details of construction, and

Figure 3 is a fragmental diagrammatic view, showing a modification of the system shown in Figure 1, wherein the brake pipe on a train of cars is employed for signaling purposes.

Description

Referring to Figure 1 of the drawings, I have shown one embodiment of a hot journal detecting and signaling apparatus for a train of cars, comprising on each car a hot journal detector indicated generally by the reference numeral 11, a combination relay and vent valve 12 controlled by detector 11 for the purpose of causing fluid under pressure to be supplied from a water raising reservoir 13 to an audible signal device, such as a whistle 14, and a manual reset indicator 15 which relay and vent valve 12 is also operative to cause a reduction of the pressure in the usual signal pipe 16 on a train of passenger cars, and further comprising on the locomotive a whistle valve 17 responsive to a reduction of the pressure in the signal pipe to cause the supply of fluid under pressure to operate an audible signal device, such as a whistle 18.

Considering the parts of the equipment in greater detail, it will be seen that the detector 11 is embodied in a suitably constructed end cover 21 which may be substituted for the usual plate type end cover, and hinged at the upper end thereof, as on a pin 22 carried by the axle journal casing 23.

The detector 11 comprises essentially two thermally responsive elements, shown as two bellows or diaphragms 24 and 25 respectively, a floating lever 26 controlled and operated by the cooperative action of bellows 24 and 25, and a valve 27 of the poppet type cooperating with the lever and operated thereby.

The bellows 24 and 25 have a suitable thermally responsive medium, such as ether or glycerin sealed therein, which reacts to variations of temperature to which the bellows is exposed to cause corresponding degrees of longitudinal expansion and contraction of the bellows.

The bellows 24 is contained within the smooth circular bore 28 of a tubular cartridge or member 29, made of copper, brass, or alloys thereof, or any other metal possessed of high heat conductivity. The cartridge 29 may be mounted in any suitable manner as, for example, by having exterior threads thereon whereby the cartridge 29 may be screwed into a threaded bore 30 in the end cover 21 to a fixed position determined by an annular shoulder 31 on the exterior of the cartridge. When the cartridge is so mounted, the inner end of the cartridge 29 extends into the cavity 32 within the journal casing 23 and terminates adjacent the end of the axle 33. One end of the bellows 24 has a circular end plate 34 attached thereto which conforms to the bore 28 and rests against the closed inner end of the cartridge 29. The opposite or free end of the bellows 24 has a piston 35 fixed thereto which is operated slidably within the bore 28 in response to expansion and contraction of the bellows 24. The piston 35 has a stem 36 attached to or formed integrally therewith, the axis of which coincides with the longitudinal axis of the bellows 24 and the outer end of which projects through a circular hole in a cap screw 37 screwed to the outer end of the car-

tridge 29. A coil spring 38, interposed between the piston 35 and the cap screw 37 in concentric surrounding relation to the stem 36, yieldingly resists the expansion of the bellows 24 and assists in the contraction of the bellows.

The bellows 25 is contained within the smooth circular bore 39 of a tubular cartridge or member 40 one end of which is closed and the other end of which is open and provided with an outwardly extending radial flange. A cap screw 41 having screw threaded engagement with an annular boss 42 is fixed on the interior face of a cover portion 43 serves to clamp the flanged end of the cartridge 40 against the end of the boss 42 in rigid secured relation thereto. The cover portion 43 is removably secured to the outer face of the end cover 21 as by a plurality of screws, not shown.

With the cover portion 43 attached to the outer face of the end cover 21 the cartridge member 40 projects into a circular recess 44 formed in the outer face of the end cover 21, the closed end of the cartridge engaging a yielding cushion 45 of suitable insulating material contained in the recess 44 whereby to assist in supporting the cartridge as well as to insulate the cartridge against the influence of the temperature within the journal cavity 32.

One end of the bellows 25 has a circular end plate 46 attached thereto which rests against the closed end of the cartridge 40. The opposite or free end of the bellows 25 has a piston 47 secured thereto which operates slidably in the smooth bore 39 of the cartridge in response to expansion and contraction of the bellows 25. A circular recess 48 is formed in the outer end of the piston 47 and a coil spring 49, partly received in the recess 48 in interposed relation between the piston 47 and the inner face of the cover portion 43 within the annular boss 42, yieldingly resists the outward expansion of the bellows 25 and exerts a force assisting the contraction of the bellows 25.

The lever 26 is pivoted at a point between the ends thereof, for example at the mid-point thereof in the manner shown, on a pin 50 which is received in a diametrically extending hole of corresponding diameter in the piston 47. The piston 47 is also provided with a longitudinally extending slot 51 for receiving the lever 26, and the wall of the cartridge 40 is provided, on diametrically opposite sides of the pin 50, with two axially extending slots 52 through which the oppositely extending arms of the lever 26 extend outwardly away from the pin 50.

As shown in Fig. 2, the wall of the cartridge 40 is provided with two diametrically opposite holes 53 adjacent the open end thereof through which the pin 50 may be inserted upon alignment with the holes 53 of the hole in the piston 47 and the hole in the lever 26. The pin 50 is slightly less in length than the diameter of the piston 47 so that when the piston is moved inwardly of the bore to effect engagement of the end plate 46 on bellows 25 with the closed end of the cartridge 40 following the insertion of the pin in the piston, the pin will be displaced longitudinally with respect to the holes 53 and thus retained in position by the wall of the cartridge 40.

One end of the lever 26 is provided with a suitably rounded head 26a for engaging the end of the stem 36 of the piston 30. The opposite end of the lever 26 is provided with a threaded hole for receiving a stop screw 54, a locknut 55 being provided for holding the stop screw in a selected fixed position.

The stop screw 54 has a rounded nut-like con-

tact head which normally has a certain predetermined clearance with respect to the end of the fluted stem 56 of the valve 27. A coil spring 51 is provided for yieldingly biasing the end of the lever 26 having the stop screw 54 pivotally on pin 50 so that the contact head 26a at the opposite end of the lever engages the end of the piston stem 36 to prevent chattering contact between the lever and the stem 36.

The poppet valve 27 is yieldingly urged by a coil spring 58 into seated relation on a valve seat formed at one end of a bushing 58a fixed in the end cover 21 and through which a fluted portion of stem 56 of the valve 27 extends in guided relation. The spring 58 is interposed between the valve 27 and a screw plug 58b screwed into the end cover 21. The plug 58b has a circular bore therein for receiving and supporting the smooth end of the valve stem 56 for slidable movement therein.

When the valve 27 is unseated in response to the clockwise pivotal movement of the lever 26 on the fulcrum pin 50, in the manner hereinafter to be described, a cavity or chamber 58c formed in the end cover 21 is connected past the valve 27 to the interior of the cover portion 43 which is, in turn, constantly open to atmosphere through one or more ports 43a, only one of which is shown.

The bellows 24 and 25 are so designed and constructed that the bellows 24 expands twice the amount that the bellows 25 expands in response to a given increase in temperature to which the bellows are respectively subjected. This characteristic relation of the two bellows 24 and 25 is illustrated in Fig. 1 by the representation of bellows 24 as having twelve convolutions while the bellows 25 has only six convolutions, that is, a ratio of volumes of two to one. On the assumption that the respective diameters of the two bellows 24 and 25 are the same and that the amount of expansion per convolution of each of the bellows is the same per degree rise in temperature, it will be seen that the expansion of the bellows 24 with relation to the expansion of the bellows 25 for any given temperature rise will bear the same ratio as the number of convolutions in the respective bellows. It is not my intention to limit the design and construction of the bellows 24 and 25 to that specifically shown, it being necessary only that the bellows 24 and 25 have a predetermined ratio of expansion and contraction per degree variation of temperature.

By reason of the ratio in the expansion characteristics of the bellows 24 and 25 it will be seen that if the temperature to which the bellows 24 and 25 are subjected is increased a uniform amount as in the case of an increase of atmospheric temperature outside the journal casing 23, the amount of clearance between the head of the stop screw 54 and the end of the fluted stem 56 in the valve 27 will remain constant or substantially so. This is so because of the fact that the ratio between the lateral movement of the fulcrum pin 50 due to expansion of bellows 25 and the distance between the fulcrum pin 50 and the contact head on the stop screw 54 will be the same as that between the outward movement of the end of lever 26 due to the expansion of the bellows 24 and the total length of the lever 26.

It will be apparent that it is possible to locate the fulcrum pin 50 at some other point than midway between the ends of the lever 26 and still maintain a constant clearance between the stop screw 54 and fluted stem of the valve 27 upon a

given rise of temperature to which both bellows 24 and 25 are exposed if the expansion characteristics of the bellows 24 and 25 are correspondingly related.

Thus, although I have shown a certain specific relation of parts and method of mounting the lever 26, it will be understood that I do not intend to limit my invention to the exact construction shown in Fig. 1.

In view of the fact that the bellows 25 is exposed at all times only to the ambient or atmospheric temperature within the cover portion 43 by reason of the connection through the port 43a to atmosphere, the fulcrum pin 50 of the lever 26 will always be positioned in accordance with the atmospheric temperature. At the same time, due to the fact that the bellows 24 is subject to the operating temperature within the journal cavity 32, a pivotal movement of the lever 26 on the pin 50 in clockwise direction will be effected due to the disproportionately greater expansion of the bellows 24 in response to the greater or higher operating temperature within the journal.

According to my invention, the stop screw 54 is so adjusted as to provide a normal clearance between the head thereof and the end of the fluted stem of the valve 27 that engagement of the head of the stop screw with the end of the valve stem 56 will be effected only after the temperature in the journal rises a certain amount above the atmospheric temperature, which amount is not attained unless the temperature in the journal rises above the normal operating temperature thereof for any given atmospheric temperature.

As indicated in Figure 1, the chamber 58c in the end cover 21 of each axle journal of a given railroad car truck is connected to a common pipe 59 by a corresponding branch conduit or pipe designated by the reference numeral 59 with the suffix letter *a*, *b*, *c*, *d*, etc., depending upon the number of axles in the truck.

The pipe 59 may be conveniently carried on the spring-supported truck frame and, therefore, it is desirable to include a flexible portion 60a, 60b, etc., in the corresponding branch pipe 59a, 59b, etc., by reason of the relative movement between the non-spring supported axle journal casing and the spring supported truck frame.

Each of the branch pipes 59a, 59b, etc., may also include a manually operated valve 61 which may be, for example, of the plug type commonly employed in air brake control apparatus on railroad cars and trains. Such a valve is desirable in order to close the communication through the branch pipe leading to the chamber 58c whenever it is desired to cut the detector 11 out of operation for any reason, such as leakage past the valve 27 or failure of the bellows 25.

The pipe 59 carried on each truck of a car is connected by a corresponding pipe 62 and 63 to the relay and vent valve 12 which is carried on the body of that particular car, close to the signal pipe 16. Due to the relative movement between the wheel trucks and the car body, the pipes 62 and 63 preferably include a flexible portion 64 as shown.

It will thus be seen that chamber 58c in the end cover 21 associated with every axle journal on a particular car is pneumatically connected to the relay and vent valve 12 whereby to effect operation thereof in response to the unseating of the corresponding valve 27 of the corresponding detector 11.

The relay and vent valve 12 comprises a suitable sectionalized casing 65 suitably formed to

accommodate parts thereof presently to be described. Essentially the relay and vent valve 12 is made up of two parts, one of which acts as a relay valve and the other of which acts as a vent valve. The relay valve portion comprises a movable abutment, in the form of a flexible diaphragm 66 of suitable material, such as rubber or reinforced rubber, secured around the periphery thereof in the casing in a manner to provide a chamber 67 at one side thereof and a chamber 68 at the other side thereof.

Suitably attached to the central portion of the diaphragm 66 within the chamber 68 is a valve 69 of the poppet type which is yieldingly biased into seated position on a valve seat, formed in the casing 65, by a coil spring 70 interposed within the chamber 67 between a follower 71 secured to the central portion of the diaphragm and a removable portion of the casing 65.

The pipes 62 and 63 are connected through a pipe T 72 and a short section of pipe 73 to the chamber 67.

The chambers 67 and 68 on opposite sides of the diaphragm 66 are connected by a passage 74 containing a restricted or choke orifice 75, the purpose of which will be explained presently.

The chamber 68 is constantly connected to and charged with fluid under pressure supplied from a suitably charged reservoir, such as the water raising reservoir 13 on the car, through a pipe 76. The water raising reservoir is charged in the usual manner through a charging pipe 77 and serves in its accustomed manner, to supply the necessary water pressure for customary uses on passenger cars.

The choke orifice 75 is so designed as to permit a reasonably prompt charging flow of fluid under pressure from the chamber 68 to the chamber 67 and through the various pipes 62, 63, 59 and branch pipes 59a, 59b, etc., to the various chambers 58c embodied in the axle journal end covers 21 on that car without overcoming the spring 70 and unseating the valve 69. When one of the valves 27 of a detector 11 is unseated, however, the fluid under pressure in chamber 67 is rapidly vented to atmosphere past the valve 27 and through the corresponding exhaust ports 43a. The restriction to the flow of fluid under pressure from chamber 68 through choke orifice 75 to chamber 67 now results in a higher pressure in chamber 68 compared to the pressure in chamber 67 due to the faster rate of reduction of pressure in chamber 67. The differential fluid pressure so created on the diaphragm 66 is accordingly effective to exert a downward force on the diaphragm 66 sufficient to unseat the valve 69 in opposition to the force of spring 70.

The vent valve portion of the relay and vent valve 12 comprises a movable abutment, illustrated as a flexible diaphragm 78 suitably attached along its periphery in the casing 65 and providing two chambers 79 and 80 on opposite sides thereof respectively. Attached to the central portion of the diaphragm 78 is a valve stem 81 on which is formed or carried a disc type valve 82. The valve 82 is contained in a chamber 83 which is connected to the chamber 80 through a port 84 in an inner wall of the casing. A coil spring 85, interposed between the valve 82 and a screw plug 86 that closes the open end of the chamber 83, urges the valve 82 upwardly into seated relation on an annular rib seat 87 formed on the casing wall within the chamber 83 and surrounding the port 84. An annular gasket 82a

is provided on the face of the valve 82 to provide a tight seal on the valve seat 87.

The chamber 78 is connected to atmosphere through a restricted orifice 81a in the casing wall, the purpose of the orifice being explained hereinafter. Chamber 79 is also connected through a passage 88 to a chamber 89 into which the fluted stem 90 of the valve 89 projects.

It will thus be apparent when the valve 89 is unseated, fluid under pressure is supplied from the water raising reservoir 13 past the valve 89 to the chamber 89, and thence through the passage 88 to the chamber 79. The fluid under pressure so supplied to the chamber 79 is effective to exert a downward force on the diaphragm 78 sufficient to cause unseating of the valve 82 in opposition to the yielding resistance of the spring 85.

The chamber 80 is constantly connected to atmosphere through an exhaust port 92. The chamber 83 is connected to the signal pipe 16 by a short branch pipe 93. Branch pipe 93 is made as short as possible in order to minimize the volume added to the volume of signal pipe 16 and prevent possible interference with the functions of the signal pipe. When the valve 82 is unseated, therefore, the fluid under pressure in the normally charged signal pipe is vented to atmosphere at a selected rate determined by the size of port 92 by way of the pipe 93, chamber 83, past the unseated valve 82 port 84, chamber 80 and port 92.

The whistle 14 and the indicator 15 are connected by a pipe 94 to the chamber 79 of the relay and vent valve 12 and are operated, as will hereinafter be described by fluid under pressure supplied thereto from the chamber 79.

The whistle 14 is of well-known construction and needs no description here except that it provides an orifice through which fluid under pressure supplied from the pipe 94 can escape to atmosphere for the purpose of producing an audible signal.

The indicator 15 comprises a tubular casing 95 having a bore at one end providing a chamber 96 at one side of a piston 97 that operates in response to the pressure of fluid supplied to the chamber 96 from the pipe 94. The piston 97 has a stem 98 suitably guided in a bore of reduced diameter formed in the casing 95 and carrying on the end thereof opposite the piston 97 a small indicator disc 99, colored red, for example, for ease of visibility. The length of the stem 98 is such that normally the red disc 99 is retracted wholly into a recess or bore 100 formed in the outer end of the tubular casing 95.

The stem 98 of the piston 97 is provided with two notches 101 and 102 spaced axially along the stem and adapted to be engaged by a loop portion of a latch spring 103 that is secured at the end thereof, as by a rivet 104 to the casing 95. The loop portion of spring 103 extends through a suitable transverse opening 105 in the wall of the casing 95 for access to the notches 101 and 102 in the stem 98. With the disc 99 in its inner position, the loop on the spring 103 engages in notch 102 to hold the disc in. Upon the supply of fluid under pressure to piston chamber 96, the latch spring 103 offers only slight resistance to the outward movement of the piston 97 and engages in the notch 101 when the piston 97 has been moved outwardly to the extremity of its travel, thereby maintaining the disc 99 in its outer or indicating position and preventing the undesired movement of the disc due to vibration etc. In the absence of fluid under pressure in the

piston chamber 96, the disc 99 may be restored manually into the recess 100 by exerting a pressure inwardly on the disc.

It will be understood that the equipment thus far described is that for each individual car of a train. In addition, I also employ on the locomotive the whistle valve 17 and the whistle 18 previously identified. Whistle valve 17 is of well-known construction and needs no description here. For a detailed description of the whistle valve 17 reference may be had to Patent No. 2,028,605.

The whistle valve is connected in the usual manner to the signal pipe 16 by a branch pipe 106, and the whistle 18 is connected to the whistle valve by a pipe 107. It will be understood that whenever a reduction of the pressure in the signal pipe 16 of at least a certain duration is effected, the whistle valve 17 is operative to cause fluid under pressure to be supplied from the signal pipe as well as a charged chamber or reservoir in the whistle valve, to the whistle 18 causing the sounding thereof.

A conventional car discharge valve 108 connected by a branch pipe 109 to the signal pipe 16 may be provided on each car in the manner shown for conventional operation thereby of the whistle valve 17 and whistle 18. Valve 108 is customarily operated by a pull cord attached to the operating handle thereof and is utilized by a member of the train crew, such as the conductor or brakeman, to signal the engineer on the locomotive. Customarily, the conductor or brakeman causes the valve 108 to vent signal pipe 16 for only a certain length of time, such as four or five seconds, which operation may be repeated at intervals. In no case is the valve 108 operated to cause a continuous reduction of pressure in the signal pipe.

Operation

A general description of the operation of the equipment will now be given. Let it be assumed that the train having the equipment described is traveling along the road and that due to failure of lubrication or other cause an axle journal begins to heat up beyond the usual normal operating temperature thereof for the particular ambient or atmospheric temperature. In such case, valve 27 of the corresponding detector 11 is unseated whenever a certain substantially uniform increase of journal temperature above the atmospheric temperature occurs. The valve 27, when unseated, causes fluid under pressure to be vented from the chamber 58c in the end cover 21 of the corresponding axle journal casing and, as previously described, from the chamber 67 of the relay and vent valve 12.

The valve 69 is accordingly unseated, as previously described, and fluid under pressure is correspondingly supplied from the water raising reservoir 13 to the chamber 79 and to the whistle 14 and piston chamber 96 of the indicator 15. The whistle 14 is therefore immediately sounded and the red disc 99 of the indicator 15 is promptly actuated outwardly from the recess 100 to a position readily visible to a member of the crew who may observe the indicator.

At the same time, the valve 82 is unseated as previously described, to effect a reduction of the pressure in the signal pipe 16. The whistle 18 on the locomotive is accordingly sounded to apprise the engineer immediately of the occurrence of the abnormal heat condition in the axle journal prior to the actual occurrence of a dangerous

heat condition in the axle journal. The engineer may, therefore, promptly apply the brakes on the train in the usual manner to bring the train to a stop and cause the necessary steps to be taken to ascertain the location of the abnormally heated journal by inspection of the indicator 15 on the various cars and by the sounding of the whistle 14 on the particular car having the abnormally heated axle journal. After so ascertaining which car has the abnormally heated axle journal, the members of the crew may thus readily find the offending journals and take the necessary steps to supply adequate lubrication to such journal to prevent the recurrence of the abnormal heat condition therein.

It will be understood that so long as the valve 27 is unseated, the valve 69 will be unseated and consequently operating pressure will be supplied to the chamber 79 of the relay and vent valve 12 as well as to the piston chamber 96 of the indicator 15 and the whistle 14.

At the same time the whistle 18 on the locomotive will continue to sound without interruption until the pressure in the signal pipe is reduced below a value sufficient to cause operation of the whistle valve and sounding of the whistle 18, which may be a matter of four or five minutes.

Should it be ascertained that the sounding of the whistles 14 and 18 and the operation of the indicator 15 is due to some other defect, such as leakage past the valve 27 or failure of the bellows diaphragm 25, a member of the crew may close the cut-out cock or valve 61 in the branch pipe to the corresponding axle journal, thereby cutting that particular detector 11 out of operation.

Whenever the valve 27 is reseated as a result of correcting the defect which initiated the operation of the equipment or whenever the valve 61 is closed, the chamber 67 at the lower side of the diaphragm 66 in relay and vent valve 12 will be quickly recharged to equalization with the pressure in chamber 68. The spring 70 thus acts to reseat the valve 69 and terminate the supply of fluid under pressure from the reservoir 13 to the chamber 79. Due to the small volume of the chambers 79, 89, 96, the pressures therein are promptly reduced due to the venting of fluid under pressure therefrom through the whistle 14 as well as through the restricted port 87a associated with the chamber 79. If a sufficiently prompt venting of fluid under pressure of these chambers occurs through the whistle 14 itself, the restricted port 87a may be dispensed with. However, if the whistle 14 is omitted or not employed and only the indicator 15 employed, then the restricted port 87a is necessary in order to effect a venting of the pressure of the fluid under pressure in the chambers 79, 89 and 96.

Upon a sufficient reduction of the pressure in the chamber 79, spring 85 acts to reseat the valve 82 and thus terminate further venting of fluid under pressure from the signal pipe 16. At the same time, due to the fact that the supply of fluid under pressure from the water raising reservoir 13 has been cut off by the seating of the valve 69, sounding of the whistle 14 is terminated.

Venting of fluid under pressure from the piston chamber 96 of the indicator 15 will not in itself effect restoration of the red indicator disc 99 to its normal retracted position shown in the drawing because, as previously explained, the latch spring 103 holds the piston stem 98 in a position to maintain the red indicator disc in a protruding position. In order, therefore, to restore the red indicator disc 99 into its retracted position

in the recess 100, pressure must be manually applied thereto by some member of the crew.

Whenever the valve 82 of the relay and vent valve 12 is reseated to cut off the venting of fluid under pressure from the signal pipe, the pressure in the signal pipe is again built-up in the usual manner to the usual pressure carried therein. Due to the fact that the branch pipe 93 is made as short as possible, the volume thereby added to the signal pipe is relatively small so that prompt recharging of the signal pipe is not interfered with. At the same time, the fact that the arrangement which I have provided does not add appreciable volume to the signal pipe 16 is advantageous in that it does not interfere with the operation of the whistle 18 in the usual manner in response to operation of the car discharge valve 108. When operation of the whistle 18 in response to operation of the car discharge valve 108 is desired, it is necessary that at least a certain amount of reduction of the pressure in the signal pipe be effected in order for the whistle valve 17 to operate in the proper manner to produce the characteristic short blast or sounding of the whistle 18. If an undesirably large volume were added to the signal pipe by reason of undesirably long branch pipes corresponding to the pipe 93, the proper reduction of the pressure in the signal pipe would not be effected and consequently the whistle valve 17 would not operate properly to effect the characteristic operation of the whistle 18 in response to operation of the car discharge valve 108.

As previously indicated, the conductor or brakeman of the train customarily holds the car discharge valve open to vent the signal pipe for a certain length of time, such as four or five seconds, in order to effect the necessary reduction of the pressure in the signal pipe 16 to cause the proper operation of the whistle valve 17 to in turn cause a relatively short blast or sounding of the whistle 18, which may be repeated at intervals for each successive operation of the car discharge valve 108.

It will be apparent, therefore, that the characteristic signal emitted by the whistle 18 in response to operation of the car discharge valve 108 is distinctly different from the characteristic signal emitted by the whistle 18 in response to the occurrence of an abnormal heat condition in an axle journal for, as previously explained, the whistle 18 is continuously sounded for a relatively long interval of time when an abnormally heated condition of an axle journal occurs. The engineer will, therefore, have no difficulty in ascertaining the fact that an abnormally heated condition exists in an axle journal, by reason of the characteristically different operation of the whistle 18 on the locomotive in response to an abnormally heated condition in an axle journal as compared to that in response to the operation of the car discharge valve 108.

Figure 3

A modified embodiment of my invention may comprise the arrangement illustrated in Figure 3. For simplicity of description parts of the equipment shown in Figure 3 corresponding to those in Figure 1 are identified by the same reference numerals without further description and only so much of the apparatus shown in Figure 3 as differs from that in Figure 1 will be described.

The embodiment shown in Figure 3 differs essentially from that Figure 1 in that operation

of the relay and vent valve 12 is effective to cause a reduction of pressure in the usual brake pipe 110 provided on railroad cars and trains of either the passenger or the freight type. This embodiment of my invention is therefore applicable to both passenger and freight trains although particularly applicable to freight trains in view of the customary absence of a signal pipe on freight trains.

As shown in Figure 1, the chamber 88 of the relay and vent valve 12 is connected by a short branch pipe 88a to the brake pipe 110.

Due to the fact that freight cars are not provided with water raising reservoirs as are passenger cars, a reservoir 13a corresponding to and serving the same function as the water raising reservoir 13 of Figure 1 is provided in the embodiment of Figure 3. The reservoir 13a is charged directly from the brake pipe by a pipe connection including a branch pipe 111 of the brake pipe 110 and a pipe 112. In order to prevent the reduction of the pressure in the reservoir 13a due to the usual reductions of pressure in the brake pipe pressure effected by the engineer or members of the crew for purposes of brake applications and also for the purpose of preventing undesirable interference with the proper reduction of the pressure in the brake pipe for normal brake applications due to the added volume of the reservoirs 13a on all cars of the train, a one-way or check valve 113 is provided in the charging communication for the reservoir 13a in the branch pipe 111. The one-way valve 113 is so disposed and arranged as to prevent back flow of fluid under pressure from the reservoir 13a to the brake pipe 110.

The branch pipe 111 is also connected to the chamber 88 at the upper side of the diaphragm 66 of the relay and vent valve 12. It will thus be seen that the reservoir 13a serves the same purpose as does the water raising reservoir 13.

In the embodiment shown in Figure 3, a whistle and whistle valve corresponding to the whistle 18 and whistle valve 17 of Figure 1 are not shown, although they may be provided in the usual manner on passenger trains without relation to the apparatus shown in Figure 3. The engineer is accordingly apprised of the occurrence of an abnormal heat condition in the journals of any car of a train by reason of the automatic application of the brakes effected on the train due to the reduction of the pressure in the brake pipe by unseating of the valve 82 of the relay and vent valve 12. At the same time, crew members may identify the particular car having the abnormally heated axle journal by the sounding of the whistle 14 and the protrusion of the red disc 19 of the indicator 15 on that car.

Having now described my invention, what I claim as new and desire to secure by Letters Patent is:

1. In a railway car axle journal having an end cover or lid closing the open end of the journal, the combination of a first thermally responsive means carried by said cover in such a manner as to be subject to and responsive to variations of atmospheric temperature only, a second thermally responsive means carried by said cover in a manner to be subject to and responsive to variations of temperature within the journal, an element to be operated carried by said cover, and means controlled and positioned by the cooperative action said first and said second thermally responsive means for effecting operation of said element whenever the temperature in the journal

13

rises a certain substantially uniform amount above the atmospheric temperature.

2. In a railway car axle journal having an end cover or lid for closing the open end of the journal, the combination of a first thermally responsive means carried by said end cover in a manner to be subject to and responsive to variations of atmospheric temperature only, a second thermally responsive means carried by said cover in a manner to be subject to and responsive to variations of temperature within the journal, a lever, a fulcrum between the ends of said lever the position of which is shifted laterally under the control of said first thermally responsive means without altering the ratio between the arms of the lever, said lever being pivoted on said fulcrum under the control of said second thermally responsive means, and an element to be operated carried by said cover and cooperating with said lever in such a manner as to be operated in response to the pivotal movement of said lever caused by said second thermally responsive means in response to a certain substantially uniform rise of temperature in the journal above atmospheric temperature.

3. Apparatus for detecting and signaling an abnormal heat condition in a railway car axle journal, comprising, in combination, a first thermally responsive bellows supported by and within the journal so as to be subject and responsive only to variations in atmospheric temperature outside the journal, a second thermally responsive bellows carried by and within the journal so as to be subject and responsive to variations of temperature within the journal, a floating lever within the journal, support means movably carried by the journal and on which said lever is pivotally mounted intermediate the ends thereof, said first bellows acting to move said support means to different lateral positions in correspondence with variations with atmospheric temperature, said second bellows acting to move one end of said lever laterally to different positions corresponding with variations of temperature within the journal, the ratio of expansion and contraction of said first and second bellows being such as to produce movement of the free end of said lever out of a certain normal position an amount proportional to the temperature rise in the journal above atmospheric temperature, and a normally seated valve so associated with said free end of said lever as to be unseated thereby only after said free end is shifted out of its normal position a certain uniform amount corresponding to a certain critical rise of temperature in the journal above atmospheric temperature.

4. Apparatus for detecting and signaling an abnormal heat condition in a railway car axle

14

journal, comprising, in combination, a first thermally responsive bellows supported by and within the journal so as to be subject and responsive only to variations in atmospheric temperature outside the journal, a second thermally responsive bellows carried by and within the journal so as to be subject and responsive to variations of temperature within the journal, a floating lever within the journal, support means movably carried by the journal and on which said lever is pivotally mounted intermediate the ends thereof, said first bellows acting to move said support means to different lateral positions in correspondence with variations with atmospheric temperature, said second bellows acting to move one end of said lever laterally to different positions corresponding with variations of temperature within the journal, the ratio of expansion and contraction of said first and second bellows being such as to produce movement of the free end of said lever out of a certain normal position an amount proportional to the temperature rise in the journal above atmospheric temperature, a normally seated valve so associated with said free end of said lever as to be unseated thereby only after said free end is shifted out of its normal position a certain uniform amount corresponding to a certain critical rise of temperature in the journal above atmospheric temperature, and a chamber normally charged with fluid under pressure, said valve being effective when unseated to vent fluid under pressure from said chamber to atmosphere.
